BOILER FEED APPARATUS

Verl E. McCoy, Chicago, Ill., and Ralph W. Anderson, Wauwateska, Wis.; said McCoy assignor or to Wilson Engineering Corporation, Chicago, Ill., a corporation of Delaware

Application June 6, 1935, Serial No. 25,218

3 Claims. (Cl. 122—442)

This invention pertains to boiler feed apparatus for various types of boilers, including locomotive boilers.

One of the advantages and objects of the invention is the provision of means for assuring a high temperature to feed water being delivered by a pump from a supply tank or other source into a boiler, using steam generated by the boiler for admixture with the water to raise its temperature.

Another object of the invention is to provide means for automatically increasing the feed water temperature just as it enters the boiler to promote at the moment of entry an increase of the water temperature to a temperature that might be uneconomical to maintain in the supply tank.

Other objects and advantages of the invention will become apparent from a perusal of the specification.

The drawings show a preferred form of the invention and a modified form thereof.

Fig. 1 is a side elevation showing a locomotive with one form of the invention applied thereto;

Fig. 2 is an enlarged detail view in cross section of a mixer employed in that form of the invention;

Fig. 3 is a side elevation showing a locomotive with another form of the invention applied thereto;

Fig. 4 is a sectional view on the line 4—4 of Fig. 3;

Fig. 5 is an enlarged detail view in section of a mixer employed in the modified form of the invention;

Fig. 6 is a partial sectional view on the line 6—6 of Fig. 5; and

Fig. 7 is a side elevation showing part of a third form of the invention.

Referring first to Figs. 1 and 2, a pipe 1 is connected with the source of feed water leading to the pump 2, the latter being driven by steam supplied through the pipe 3. The pump delivers the feed water into the pipe 4 through a check valve 5, interposed in the line to prevent reverse flow of the water and thence into Venturi-type mixer generally designated at 6. From the mixer, the water then passes through a boiler stop and check valve 7 into the water space in the boiler. The pump is intended to deliver water into the pipe 4 at a pressure higher than the boiler pressure, and in any case will deliver the water into the boiler whether or not heat is added to it in the mixer.

The mixer consists of a nozzle 8, a chamber 9, and a Venturi tube 11.

A pipe 12 is connected with the steam space of the boiler for delivering live steam preferably at or near the boiler pressure into the chamber of the mixer. A valve 13 will ordinarily be interposed in the pipe 12 so that the steam may be shut off manually from this pipe, whenever desired, or a remotely controlled valve may be employed if desired. Also, if desired, a check valve 14 may be positioned in the pipe 12 to prevent the feed water from flowing into the steam space, but permitting steam to flow toward the mixer.

In the usual operation of the device, when the feed water pump starts, the water delivered by the pump will have its static pressure temporarily decreased as it passes through the chamber 9 between the nozzle and the Venturi tube. The mixer is so designed that this pressure will be lowered at least a few pounds below the pressure of the steam supplied by the pipe 12, hence this pressure differential will entrain steam from the pipe 12 and mixing of the steam and water will occur in the Venturi tube. As the water emerges from the Venturi tube its static pressure is restored to approximately its former pressure.

The feed water delivered by the pump may have a temperature ranging anywhere from atmospheric temperature up to approximately its atmospheric boiling point, depending upon the amount of heat supplied to it previously in the supply tank or elsewhere. In any event, however, the admixture of the live steam with this water will raise its temperature greatly and will assure the delivery of the feed water into the boiler at temperatures which will not be so low as to be harmful. The temperature increase thus obtained may range in practice anywhere from 50° to 150° F. or more, up to the boiler temperature.

Not only is the temperature of the water raised to a safe temperature for feed water injection, but use of this device further emulsifies anti-foaming compounds which may have been previously introduced into the water and increases their effectiveness.

Ordinarily the valve 13 will be open and if the pipe 12 is not connected to the turret but is connected as shown, the check valve 14 may be omitted, since some initial delivery of water through this pipe into the boiler is not harmful. While an automatically controlled valve might be employed to close the steam supply pipe 12 when the feed pump is not operating, such provision is not necessary. The boiler steam pres-

sure may be maintained at all times in the pipe 12 and the live steam may thus be held ready for use any time the feed pump starts. In this manner the automatic mixing of live steam with the 5 feed water will be assured without requiring any complicated mechanism. Whenever the pump stops, the flow of steam through the pipe 12 also will stop, the check valve 5 serving to prevent the escape of steam back toward the pump.

10 In the other form of the invention shown in Figs. 3 to 6, inclusive, provision is made for using exhaust steam whenever it is available and live steam when the exhaust steam supply is lacking, for heating the water immediately prior to its 15 entry into the boiler.

A pipe 21 is connected with a source of feed water, for example a tender tank, or a special feed water compartment, and leads to the pump 22, the latter being driven by steam supplied 20 through the pipe 23. This pump delivers the feed water into the pipe 24 through a check valve 25 which is interposed in the line to prevent reverse flow of the water and thence into a Venturi type mixer, generally designated as 26. From the 25 mixer, the water then passes through a boiler stop and check valve 27 into the water space in the boiler. The pump is intended to deliver water into the pipe 4 at a pressure higher than the boiler pressure.

30 The mixer consists of a chamber 28 into which a nozzle 29 projects. A needle valve 31 is employed to regulate the effective area of the nozzle and is secured to a piston 32 located in the cylinder 33. A pipe 34 is connected with the steam 35 space in the boiler and maintains boiler pressure constantly on the adjoining side of the piston. The pipe 24 is connected with the inlet port 35 and delivers water into the chamber 36 always at a pressure higher than the boiler pressure. In 40 order that the pump pressure, acting through the holes 37, may not drive the piston to the left and open the nozzle wide, a spring 38 is located as shown to partially offset the excess of water pressure. It will be of such a strength that when the 45 pump stops and the water pressure at the port 35 ceases, the needle valve will close, but will open when the pump starts. As the velocity of the pump is increased and the water pressure thereby increases, the needle valve will recede from 50 the nozzle outlet. Thus by regulating the effective area of the nozzle aperture the pressure of the water delivered from the nozzle into the chamber 28 may be held within close enough limits as to assure that the jet of water projected 55 into the frusto-conical members 39 will produce a high vacuum in the chamber whereby exhaust steam at any available pressure may thus be introduced through and between the cones into the water stream. Also, this method of regulating 60 the nozzle orifice avoids placing an undue load on the pump when it is operating at full capacity.

Preferably the members 39 are formed integrally with the Venturi tube 41, with suitable 65 spacing and apertures as shown, and the tube is connected with the pipe 42 for delivering water into the boiler. The exhaust steam which is drawn into the water stream will be condensed thereby and will, when an ample supply of the 70 exhaust steam is available, impart enough heat to prevent the introduction of harmfully cool water into the boiler.

Should the supply of exhaust steam be insufficient for properly heating the water, or be entirely lacking, as may happen when the engine 75

is drifting, means are provided for introducing live steam to supplement or replace the action of the exhaust steam. Accordingly, a pipe 43 is connected to the steam space in the boiler and to the vacuum chamber in the mixer and is provided with a thermostatically controlled valve 44 whose temperature sensitive element is disposed in the pipe 42. Hence when the feed water emerging from the Venturi tube is below a predetermined desired temperature, the valve 44 will become 10 opened and live steam will be introduced into the water in amount sufficient to create the water temperature desired.

The exhaust steam which is supplied to the mixer will ordinarily be picked up from the exhaust of the cylinders, a pipe 45 being provided for this purpose and being connected to the cylinder exhaust duct in any suitable manner. The point of connection and the manner of connection are not important. This pipe will preferably 20 be installed, as shown, either on the exterior of the boiler shell, or it may be located inside the front end. At its highest point a vacuum relief valve 46 of ordinary and suitable construction will be installed to admit air to this pipe, should a partial vacuum therein occur. The mixer is connected by a short pipe 47 to the pipe 45.

It is contemplated that when the pump is starting some water will be spilled by the mixer until the velocity of the water jet is sufficient to 30 cause all of the water to bridge the gap and enter the Venturi tube. This spilled water will be allowed to flow into the pipe 48 and will be conducted rearwardly through the check valve 49 preferably back into the feed water supply tank, 35 tender tank or other storage space for feed water, but might be allowed to spill on the ground. Because of the position of the connection of pipes 47 and 45, none of the spilled water may go over into the pipe 45 and enter the engine cylinders. 40 Also the top of the loop in the pipe 45 is high enough so that, when the locomotive is on the steepest downgrade that may be encountered and when the forward end of the locomotive is down-hill any water which might flow forwardly 45 through the pipe 48 and leak past the check valve 49 cannot enter the engine cylinders.

The second described form of the invention has the particular advantage of using exhaust steam, a waste product, for raising the temperature of 50 the feed water. When the mixer is properly designed the feed water from the tender tank can be raised in temperature from 32° F. to the saturation temperature of the exhaust steam available for heating.

In the operation of the apparatus shown in Figs. 3 to 6, inclusive, whenever the feed pump is started by opening the steam supply valve located in the cab, the water delivered through the pipe 24 will, in a short time, produce a vacuum 60 in the chamber 28 and draw in exhaust steam and cause it to be mixed in the Venturi tube with the feed water, if exhaust steam is available. Otherwise, in the absence of exhaust steam or due to an insufficient supply of exhaust steam, 65 the delivery of water into the pipe 42 at a temperature below some predetermined temperature will cause the valve 44 to open up and admit live steam directly from the boiler into the mixer. Hence at all times the apparatus insures that feed water delivered into the boiler will not have a harmfully low temperature. The capacity of the mixer and the supply of steam will be such 70 that enough steam can always be added to suf- 75

ficiently increase the feed water temperature for the protective purposes desired.

Fig. 7 illustrates a third embodiment of the invention. In this form of the invention the mixer shown in Fig. 5 is employed with the exception that the live steam supply pipe 43 is omitted. This modified mixer is generally indicated as 26' in Fig. 7. The apparatus shown in this figure is intended to replace the apparatus shown in the similar area of Fig. 3, the pipe 24' being connected to the pipe 24, the pipe 48' being connected to pipe 48, 45' to 45, the relief valve 46' being identical with and a substitute for the relief valve 46. In this modification, live steam from the boiler, acting through the pipe 34' regulates the needle valve, while the water is supplied to the mixer from the pipe 24', while the exhaust steam is supplied by the pipe 47'. The Venturi tube 41' is connected to the pipe 42' and delivers the water through a check valve 50, thence into the entering end of another Venturi-type mixer which is identical in design with the mixer shown in Fig. 2. This mixer is designated 6' and has a Venturi tube 11' which delivers the water through the stop and check valve 27' into the boiler. A pipe 12' controlled by the valve 13' supplies live steam from the steam space in the boiler to this second mixer. This modified form, therefore, consists substantially of the mixers shown in Figs. 2 and 5 arranged in series, omitting the live steam supply to the exhaust steam mixer and supplying the live steam only into the second mixer. With this arrangement, feed water having a temperature even as low as 32° F. may receive a boost in temperature up to the saturation temperature of whatever exhaust steam is available for heating. Whether or not this water is then sufficiently heated, it will, in its passage through the second mixer, have its static pressure sufficiently lowered so that live steam from the boiler may be mixed therewith, as will be understood from the previous description of Fig. 2. In the second mixer the water may receive a further boost in temperature which may range up as high as a 150° F. increase, depending upon the proportioning of the parts. Thus when a high pressure boiler is being fed with the apparatus now being described, the feed water temperature may be raised as high as 300° F. and higher, a part of the heat being recovered from the exhaust steam and additional heat being supplied by live steam to make certain that feed water cannot enter the boiler at such a low temperature as to do damage therein.

Referring now to Fig. 3, the pump 22 when running is always delivering a considerable amount of exhaust steam, hence arrangements are herein made to condense that steam by connecting the pipe 51, as shown, to a jet condenser 52 and causing the exhaust steam to inject water from the pipe 51 into the return pipe 48. Thus the heat of this exhaust steam is saved.

While the invention is illustrated as being applied to a locomotive, it is obviously capable of being used with other boilers, including stationary boilers of various kinds. Furthermore, the drawings and specification illustrate and describe merely a few embodiments of the invention. Va-

riations and other modifications of the invention are contemplated and may be employed without any departure from the spirit and scope of the invention, especially as defined in the claims which follow.

Having shown and described our invention, we claim:

1. In combination with a locomotive boiler, means including a pump for withdrawing feed water from a supply source and delivering it at a pressure exceeding the existing boiler pressure, means for temporarily increasing the water velocity and decreasing the static water pressure to a range below the pressure of exhaust steam from the locomotive cylinders, means controlled by the delivery pressure of said pump for regulating said water pressure and velocity, means for introducing cylinder exhaust steam into said water while at said lowered pressure, and means for decreasing the velocity of the water and raising its pressure after said introduction of exhaust steam to an excess over the boiler pressure and delivering the same into the boiler.

2. In combination with a locomotive boiler, means including a pump for withdrawing feed water from a supply source and delivering it at a pressure exceeding the existing boiler pressure, means for temporarily increasing the water velocity and decreasing the static water pressure to a range below the pressure of exhaust steam from the locomotive cylinders, said means including a nozzle and a valve for regulating the effective area of the nozzle, means controlled by the delivery pressure of said pump for operating said valve to regulate the flow of water through said nozzle for controlling said static water pressure, means for introducing cylinder exhaust steam into said water while at said lowered pressure, and means for decreasing the velocity of the water and raising its pressure after said introduction of exhaust steam to an excess over the boiler pressure and delivering the same into the boiler.

3. In combination with a boiler, means including a pump for delivering feed water at a pressure exceeding the boiler pressure, a mixer including a chamber, a combining tube and a jet for projecting the water delivered by the pump through the chamber into the tube, means for introducing cylinder exhaust steam into said chamber, a needle valve for regulating the orifice in the jet, a cylinder having a piston therein rigidly connected with said valve, the side of the piston toward said valve being exposed to the delivery pressure of the pump, a pipe communicating from the steam space in the boiler to the opposite end of said cylinder to subject said piston to the boiler pressure, a pipe connected for delivering water from the pump to the intake end of said jet, and a pipe connected with the combining tube for delivering a mixture of water and steam into the boiler, said piston serving to operate said valve to increase the effective area of the jet as the pump delivery pressure increases and decrease said area as said pump pressure decreases.
